UNITED STATES PATENT OFFICE

WARNER R. BUXTON, OF LONGMEADOW, MASSACHUSETTS

DESIGN FOR A BILL FOLD

Application filed June 6, 1930. Serial No. 35,947. Term of patent 14 years.

To all whom it may concern:

Be it known that I, WARNER R. BUXTON, a citizen of the United States, residing at Longmeadow, in the county of Hampden and State of Massachusetts, have invented a new, original, and ornamental Design for Bill Folds, of which the following is a specification, reference being had to the accompanying drawing, forming part thereof.

Fig. 1 is a front elevational view of a bill fold embodying my new design; and

Fig. 2 is an end elevational view of the bill fold.

The design appears wholly on the front

side of the bill fold, shown in Fig. 1,—the reverse side being plain. The characteristic feature of the design resides in a pair of curving lines disposed one on each side of the center fold. These lines start near the upper corners of the bill fold and extend downwardly toward the central part of the lower edge of the bill fold in approximately converging relation.

I claim:

The ornamental design for a bill fold substantially as shown and described.

WARNER R. BUXTON.
